UNITED STATES PATENT OFFICE.

FRANCOIS LETOURNEAU, OF PROVIDENCE, RHODE ISLAND.

DANCING-FIGURE TOY.

1,368,738.

Specification of Letters Patent. Patented Feb. 15, 1921.

Application filed May 1, 1920. Serial No. 378,201.

To all whom it may concern:

Be it known that I, FRANCOIS LETOURNEAU, a citizen of the United States, residing at Providence, in the county of Providence and State of Rhode Island, have invented certain new and useful Improvements in Dancing-Figure Toys, of which the following is a specification, reference being had to the accompanying drawings.

10 This invention relates to an improved figure toy and an object is to provide a toy including a figure having pivoted legs and arms and mounted upon a spring arm of a fulcrumed bar, whereby upon striking one 15 end of the bar with a maul and increasing or decreasing the blows, the figure toy will vibrate and the legs and arms will vary in movements in the act of imitating clog dancing or buck-and-wing dancing.

20 Another object is to provide a toy of this kind which will create considerable amusement for children as well as grown people and furthermore to provide a toy which is very simple, efficient and practical in construction and capable of being cheaply made 25 and sold at a reasonable profit.

Still another object is to provide a toy, wherein suitable means such as rubber bumpers or the like are interposed between 30 the oscillatory board and the base in order to eliminate the noise incident to the oscillatory board being struck by a maul to cause the toy to vibrate and produce various dancing steps.

35 A further object is to provide a dancing toy of this kind wherein the oscillatory board is pivotally mounted with the figure toy disposed over one end of the board to hold said end normally in a downward position with the toy supported upon a spring

40 arm projecting from the opposite end of the oscillatory board so that the striking of the end of the board carrying the spring arm will cause the spring arm to vibrate and as 45 the arm vibrates and the legs of the figure shake in producing various steps, the board under the feet will strike the feet and therefore vary the movements of the legs and feet of the figure toy.

50 Furthermore by the provision of the rubber bumpers the noise that would otherwise be created due to the striking of the oscillatory board with the maul will be eliminated.

A still further object is the provision of a 55 cushion member adjacent the fulcrum of the

oscillatory board serving as a bearing and also thereby eliminating noise as the toy is in operation.

Additionally the invention aims to provide improved means for mounting the 60 spring arm on the oscillatory board, said means being used as a striker block on the oscillatory board for the maul so that the blows of the maul will not engage the board which carries the spring arm. 65

While the design and construction at present illustrated and set forth is deemed preferable, it is obvious that as a result of a reduction of the invention to a more practical form for commercial purposes, the invention 70 may be susceptible to changes, and the right to these changes is claimed, provided they are comprehended within the scope of what is claimed.

The invention comprises further features 75 and combination of parts, as will be herein-after set forth, shown in the drawings and claimed.

In the drawings:-

Figure 1 is a plan view of the toy with 80 the dancing figure removed,

Fig. 2 is a view in side elevation of the dancing toy, showing the maul 10 in position to strike the striking block,

Fig. 3 is a view in front elevation of the 85 figure toy, and

Fig. 4 is a side view of the body of the figure toy showing the various joints between the legs and arms with the body.

Fig. 5 is a detail view showing the forward portions of the upper ends of the legs rounded instead of angular to insure freedom of movement of the legs, should this construction be desired.

Referring to the drawings, 1 designates a 95 base board which may be any suitable width, length and any configuration, preferably as shown, and which may be supported on any suitable support such as a table or the like. Mounted upon the board 1 is a pair of bearing blocks 2 having upwardly projecting parts 3 in which the fulcrum pin 4 is mounted. The fulcrum pin 4 passes through the oscillatory board or member 5 which is interposed between the bearing blocks which 100 are secured to the board 1 as at 6.

Secured to the oscillatory member or board 5 immediately adjacent the fulcrum pin and under the same is a rubber bumper or member 7 which is designed to engage the 110

board 1 in order to hold the fulcrum pin in engagement with the walls of the bearings of the parts 3, thereby eliminating the noise incident to the board 5 being oscillated. 5 While the rubber bumpers or members 7 are used in the construction of the device when the oscillatory member 5 is fulcrumed between the bearing blocks it is obvious that the rubber bumpers or members 7 can be 10 omitted if desired in order to facilitate the freedom of movement of the oscillatory member. However, when the bearing blocks are used to rest upon a table or the like it is very essential to employ the rubber bumpers 15 or members 7 in order not to scar the surface of the table. In fact, the bearing blocks may rest upon any suitable protecting means such as felt or the like so as to prevent the blocks from scarring or injuring the surface of the 20 table.

One end of the board 1 is provided with a rubber bumper 8 to be normally engaged by one end of the oscillatory member 5. The other end of the board or base 1 has a rubber bumper 9 with which the opposite end of the oscillatory member 5 engages as said member is struck with a maul such as shown at 10 in the drawings. By means of these bumpers 8 and 9 the noise which would 25 otherwise occur incident to the movement of the member 5 in striking the opposite ends of the base 1 is eliminated.

Secured by suitable screws or the like 30 to the oscillatory member on one end thereof is a cross piece 11 the upper surface of which is covered with a rubber sheeting 12 so as to cushion the maul and eliminate the noise when in the act of imparting blows to the striking block or cross piece 11. The cross 35 piece or striker block 11 has on its under surface a channel 13 which receives the end 14 of a spring arm 15. The extremity of the end 14 of the arm 15 is bent downwardly as at 16 and engaged into the oscillatory member 5 thereby preventing the arm 15 from 40 twisting or turning. This spring arm extends from under the striker block and curves upwardly as at 17 and inclined at 18, then its extremity 19 terminates in a plane 45 substantially parallel with the oscillatory member 5. The extremity of the part 19 of the arm terminates in a plate 20 which is secured by screws 21 to the body of the figure 50 toy. In fact, the extremity of part 19 of the spring arm terminates at a point over one end of the oscillatory member 5 so that 55 the figure toy may be supported over said end in a position so that the heels of the feet of the toy are spaced a short distance from the member 5, while the toe portions of the feet are barely in contact with the member 5, that is when the spring arm is at rest.

In Fig. 1 of the drawings, the figure toy is illustrated as being dressed in men's attire while in Figs. 3 and 4 the figure is

shown with the clothing removed. The figure toy comprises a body 22 having a head 23 fixed thereon. The arms 24 are pivotally connected to the shoulders of the body by means of the screws 25, there being washers 26 between the arms and the body so that the arms can freely move. Each of the arms comprise two sections 26^a and 27. The section 26 is bifurcated as at 28 to receive the extension 29 of the section 27, there being a 75 pivot pin 30 passing between the two sections in order to pivotally connect them.

The lower part of the body 22 is provided with a pair of bifurcations 31 which receive the extensions 32 of the legs 34. A single 80 pivot pin 35 passes transversely of the body and through the extensions 32 in order to pivotally connect the legs to the body. It will be noted that the bifurcations 31 extend downwardly and toward the rear, thereby 85 forming abutments 36 to avoid excessive movement of the legs relatively to the body. The forward portions of the upper ends of the legs are of an angular shape as indicated at 37 in order to engage the forward 90 portion of the bottom walls of the bifurcations 31 to avoid excessive movement of the legs in a forward direction. While the forward portions of the upper ends of the legs are of angular shape for the purpose of contacting with the forward portions of the bottom walls of the bifurcations 31 to avoid 95 excessive movement of the legs, the upper edges of these angular portions are spaced sufficiently from the bottom walls of the 100 bifurcations in order to permit of freedom of movement of the legs. However, it is obvious that these portions of the upper ends of the legs may be rounded as shown in Fig. 5 instead of angular in order to insure freedom of movement of the legs. Each of the 105 legs consists of two sections 39 and 40. The section 39 is bifurcated at 41 and engaging the bifurcation is the extension 42 of the section 40 of the leg. Suitable pivot pins 110 43 pass through the joined sections of the two legs so as to pivotally unite the two sections whereby as the spring arm is vibrated the legs will shake and tend to produce various movements in clog and buck-and-wing 115 dancing. The forward portions of the upper ends of the sections 40 of the legs are angular as shown at 44 in order to abut the bottom wall of the bifurcations 41 of the sections 39 thereby avoiding excessive movement 120 of the sections 40 of the legs in a forward direction.

It will be noted that by using the maul shown in the drawings in order that the enlarged end of the maul may strike the 125 buffer sheet on the striker block 11, the oscillatory member 5 will oscillate on its fulcrum and cause the spring arm to vibrate. The vibrating of the arm will cause the figure toy to shake and the legs and arms 130

thereof will tend to move in imitation of the various steps in clog and buck-and-wing dancing. One end of the oscillatory member 5 will strike against the feet of the figure 5 toy and cause the legs to move in imitation of various dancing steps. It is to be noted that a toy of this kind will cause a great deal of amusement not only to children but also for grown people.

10 The invention having been set forth, what is claimed as new and useful is:—

1. In a toy as set forth, a base, an oscillatory member fulcrumed thereon, a yieldable spring arm connected to one end of the oscillatory member and extending upwardly and across the fulcrum of the member and terminating at a point over the other end of the member and provided with a figure toy on said free and unattached end, the end of 15 said member to which the yieldable spring arm is connected adapted to be struck, whereby the arm and toy and the oscillatory member will move, said member coöperating with the feet of the toy, thereby causing the legs and arms of the toy to portray 20 various dancing steps.

2. In a toy as set forth, a base, an oscillatory member fulcrumed thereon, a yieldable support connected to one end of the member 30 and extending upwardly and over the fulcrum of the member and terminating in a free and unattached end, a loose jointed figure toy connected to said free and unattached end and supported over the end of 35 the member opposite the end to which the yieldable support is connected, whereby as the end of the member carrying the support receives blows, the support and the figure toy will vibrate and the member will oscillate, all three coöperating to cause the legs and arms of the toy to imitate various 40 dancing movements.

3. In a toy as set forth, a base, an oscillatory member fulcrumed thereon, a yieldable support connected to one end of the member and extending upwardly and over the fulcrum of the member and terminating in a free and unattached end, a loose jointed figure toy connected to said free and unattached end and supported over the end of the member opposite the end to which the yieldable support is connected, whereby as the end of the member carrying the support receives blows, the support and the figure toy will vibrate and the member will oscillate, all three coöperating to cause the legs and arms of the toy to imitate various dancing movements.

4. In a toy as set forth, a base, an oscillatory member fulcrumed thereon, a yieldable support connected to one end of the member and extending upwardly and over the fulcrum of the member and terminating in a free and unattached end, a loose jointed figure toy connected to said free and unattached end and supported over the end of the member opposite the end to which the yieldable support is connected, whereby as the end of the member carrying the support receives blows, the support and the figure toy will vibrate and the member will oscillate, all three coöperating to cause the legs and arms of the toy to imitate various dancing movements, and means for preventing the yieldable support from turning or twisting 50 relatively to the oscillatory member. 60

4. In a toy as set forth, a base, an oscillatory member fulcrumed thereon, a yieldable support connected to one end of the member and extending upwardly and over the fulcrum of the member and terminating in a free and unattached end, a loose jointed figure toy connected to said free and unattached end and supported over the end of the member opposite the end to which the yieldable support is connected, whereby as 70 the end of the member carrying the support receives blows, the support and the figure toy will vibrate and the member will oscillate, all three coöperating to cause the legs and arms of the toy to imitate various dancing movements, cushioning members for the opposite ends of the oscillatory member, and cushioning means carried by the oscillatory member at a point adjacent its fulcrum 75 in order to insure holding the fulcrum pin 80 in its bearing against a rattling movement in its bearings.

In testimony whereof I hereunto affix my signature.

FRANCOIS LETOURNEAU.
